CLAIM

The ornamental design for a faucet handle, as shown and described.

DESCRIPTION

FIG. 1 is a perspective view taken from the top and left side of a faucet handle showing my new design;

FIG. 2 is a left side elevational view thereof, the right side being the mirror image of the left side;

FIG. 3 is a top plan view thereof;

FIG. 4 is a front elevational view thereof;

FIG. 5 is a rear elevational view thereof; and

FIG. 6 is a bottom plan view thereof.

FIG. 1

FIG. 2

UNITED STATES PATENT AND TRADEMARK OFFICE
CERTIFICATE OF CORRECTION

PATENT NO. : Des. 323,022

DATED : January 7, 1992

INVENTOR(S) : Christian M. Ragonot

It is certified that error appears in the above-identified patent and that said Letters Patent is hereby corrected as shown below:

In the claim, the words "or the like" are inserted between "handle" and the comma.

In the description of Fig. 1, the words "or the like" are inserted between "handle" and "showing".

Signed and Sealed this
Twenty-ninth Day of June, 1993

Attest:

MICHAEL K. KIRK

Attesting Officer

Acting Commissioner of Patents and Trademarks
